UNITED STATES PATENT OFFICE.

CHARLES BLESCH, OF NEWPORT, KENTUCKY, ASSIGNOR TO THE CRANE & BREED MANUFACTURING COMPANY, OF CINCINNATI, OHIO, A CORPORATION OF OHIO.

DESIGN FOR A BURIAL-CASKET HANDLE.

41,331.

Specification for Design.

Patented Apr. 25, 1911.

Application filed February 8, 1911. Serial No. 607,439. Term of patent 7 years.

To all whom it may concern:

Be it known that I, CHARLES BLESCH, a citizen of the United States, residing at Newport, in the county of Campbell and State of Kentucky, have invented a new, original, and ornamental Design for Burial-Casket Handles, of which the following is a specification, reference being had to the accompanying drawing, forming a part thereof.

The figure is a front elevation of a burial-

casket handle, showing my new design, with one tipped end of the handle-bar broken away.

I claim:—

The ornamental design for a burial-casket handle as shown.

CHARLES BLESCH.
